(57) **CLAIM**

We claim the ornamental design for a screw-top container, such as a metal or plastic container, as shown and described.

DESCRIPTION

FIG. 1 is a perspective view of an embodiment of the claimed design;

FIG. 2 is a front view of the claimed design of FIG. 1;

FIG. 3 is a rear view of the claimed design of FIG. 1;

FIG. 4 is the left side view of the claimed design of FIG. 1;

FIG. 5 is the right side view of the claimed design of FIG. 1; and,

FIG. 6 is a top view of the claimed design of FIG. 1.

The ornamental design which is claimed is shown in solid lines in the drawings. The broken lines shown are included for the purpose of illustrating the unclaimed portions of the container and form no part of the claim.

1 Claim, 6 Drawing Sheets
